UNITED STATES PATENT OFFICE.

LUKE F. GILLESPIE, OF NEWBURGH, NEW YORK, ASSIGNOR TO JONES & HARDY, OF HUDSON, NEW YORK, A CORPORATION OF NEW YORK.

PICKER-STICK CONNECTION FOR LOOMS.

No. 895,252.

Specification of Letters Patent.

Patented Aug. 4, 1908.

Application filed November 18, 1907. Serial No. 402,627.

To all whom it may concern:

Be it known that I, LUKE F. GILLESPIE, a citizen of the United States, residing at Newburgh, in the county of Orange and State of New York, have invented an Improvement in Picker-Stick Connections for Looms, of which the following is a specification.

My invention relates to an improvement 10 in picker-stick connections for looms. Heretofore the lug strap connecting the picker-stick to the sweep-stick has ordinarily been made of leather, the relation of which was maintained to the picker-stick by a loop of 15 leather secured to holes made in said stick. The adjustment of the lug strap was effected by other holes in the picker-stick and these holes weakened the picker-stick and the lug strap would stretch and wear.

20 The object of my invention is to increase the useful life of the picker-stick and to lend prominence to the other parts by the employment of a lug strap of substantial character and means for adjustably fixing the 25 position of the same upon the picker-stick without the necessity of perforating the said stick.

In carrying out my invention, I provide a lug strap of metal of elongated U-form to 30 straddle the picker-stick, a bunter of leather or similar material in the bend of the strap securely held in place, and eyes in the other or free ends of the lug strap for a bolt for connecting the strap to the sweep-stick of 35 the loom.

The picker-stick is of usual character (without weakening holes), pivotally connected to a base of the loom and at its upper end provided with a picker to hit the shuttle 40 and throw it across the loom.

I provide means preferably in the form of 45 adjusting clips secured to the picker stick both above and below the lug strap for positioning the lug strap as desired and adjusting the same to regulate the extent of movement or travel imparted to the said stick and so to control the force of the blow upon the shuttle. These clips are preferably made with curved parts for the eyes of the lug- 50 strap to bear against.

In the drawing, Figure 1 is a side elevation and Fig. 2 an edge elevation representing the devices of my improvement and Fig. 3 is a sectional plan at the dotted line z, z , of 55 Fig. 1.

The picker stick b is connected by a pivot shaft 2 to a cast base a of the loom. The picker stick is preferably of wood and of usual character, and at the upper free end thereof a picker c also of usual character is 60 secured to the stick against which the shuttle strikes at the end of its movement and by which with the further movement of the picker-stick the shuttle is thrown from one side of the loom to the other.

d represents the lug strap and e the sweep stick. The latter is of the usual construction in looms. The lug-strap however, according to my invention, is made of metal of elongated U-form to straddle the picker-stick and at the free end of the lug-strap d the same receives between the parts the sweep-stick e and a bolt 3 passes through the parts connecting them together. The lug-strap passes at each side of the picker- 75 stick b and in the bend thereof there is a bunter f of leather or other suitable material connected in place by a bolt 4 which passes through the lug-strap and through the bunter; the surface of the bunter bearing 80 against an edge of the picker-stick.

I provide means for positioning the lug-strap and determining the relation thereof along the picker-stick and its distance from the pivot shaft 2, and this means is preferably in the form of adjusting clips. These clips are made alike but reversed in position. Each clip comprises a yoke h of metal with free threaded ends on which there are nuts h^1 and a plate i notched and provided with 90 forked or curved ends i^1 . The plate i presses against the back edge of the picker-stick while the bent portion of the yoke passes around the front edge of the picker-stick and the threaded ends of the yoke pass 95 through holes in the plate and the nuts clamp the parts together upon the picker-stick. The curved ends pass over the opposite faces of the picker-stick toward the center and when these clips are arranged in opposite positions the said curved ends i^1 come closely adjacent to the opposite top and bottom edges of the lug-strap d ; in fact the lug-strap d rests upon the curved ends of the lower clip rocking thereon with the 100 swinging movement of the picker-stick and should the yoke strap as the result of the momentum of the parts tend to rise from its support on the lower clip it will momentarily come in contact with the curved ends of the 105 110

upper clip, its upper movement being arrested and it temporarily rocking on the curved ends of the upper clip.

The greater the movement to be given to 5 the picker-stick the nearer will the lug-strap be brought to the pivot shaft 2 because the sweep-stick *e* has a recognized amount of movement and the smaller the extent of movement to be given the picker-stick the 10 further away from the pivot shaft 2 is the lug-strap placed. In this way the extent of movement desired is easily adjusted or regulated.

The parts are strong, substantial, readily 15 secured and adjusted. Their use does not make it necessary to weaken the picker-stick by making holes therein, consequently the initial strength of the picker-stick is maintained and the parts being of substantial character their useful life is very considerable.

I claim as my invention:

1. The combination with a picker-stick and a sweep-stick, of a metal lug-strap adapted 25 to straddle the picker-stick, a bolt connecting the lug-strap to the sweep-stick, a bunter and bolt for securing the same between parts of the lug-strap and separate and independent adjustable means secured to the picker- 30 stick both above and below the lug-strap for adjustably locating the lug-strap and guiding the same.

2. The combination with a picker-stick and a sweep-stick, of a metal lug-strap adapted 35 to straddle the picker-stick, a bolt connecting the lug-strap to the sweep-stick, a bunter and bolt for securing the same between parts of the lug-strap and spaced apart, separate and independent means secured to the picker-stick both above and below the lug-strap for locating the lug-strap and guiding the same.

3. The combination with a metal base and a tapering wooden picker-stick and wooden 45 sweep-stick, of a metal lug-strap of elongated U-form adapted to straddle the picker-stick, a bolt connecting the lug-strap at its free ends to one end of the sweep-stick, a bunter

of leather or similar material within the bent portion of the lug-strap with the surface 50 thereof coming against the edge of the picker-stick, a bolt for securing the bunter to the lug-strap and spaced apart, separate and independent means secured to the picker-stick both above and below the lug-strap for locating the lug-strap along the picker-stick 55 and guiding the same.

4. The combination with a metal base and a tapering wooden sweep-stick, of a metal lug-strap of elongated U-form adapted to 60 straddle the picker-stick, a bolt connecting the lug-strap at its free ends to one end of the sweep-stick, a bunter of leather or similar material within the bent portion of the lug-strap with the surface thereof coming against the edge of the picker-stick, a bolt for securing the bunter to the lug-strap and means each comprising a yoke straddling the picker-stick, a plate with holes engaged by 65 the yoke and nuts for securing the parts together and curved ends to the said plate coming at either side of the picker-stick both above and below the lug-strap for adjustably 70 locating the lug-strap and guiding the same.

5. The combination with a metal base and a wooden sweep-stick, of a metal lug strap adapted to straddle the picker-stick, a bolt connecting the lug strap to one end of the sweep-stick, a bunter of leather or similar material secured within the lug strap, with a surface 75 thereof coming against the edge of the picker-stick and means each comprising a yoke straddling the picker-stick, a plate with holes engaged by the yoke, and nuts for securing the parts together, and curved ends 80 to the said plate coming at either side of the picker-stick both above and below the lug strap for adjustably locating the lug strap and guiding the same.

Signed by me this 4th day of November, 90
1907.

L. F. GILLESPIE.
